UNITED STATES PATENT OFFICE.

GUSTAV L. JAEGER, OF NEW YORK, N. Y.

APPARATUS FOR DRYING PAPER, &c.

SPECIFICATION forming part of Letters Patent No. 359,446, dated March 15, 1887.

Application filed October 7, 1886. Serial No. 215,573. (No model.)

To all whom it may concern:

Be it known that I, GUSTAV L. JAEGER, a citizen of the United States, residing at New York, in the county and State of New York, have invented new and useful Improvements 5 in Apparatus for Drying Paper and other Articles, of which the following is a specification.

The object of this invention is to provide an 10 apparatus by which fabrics can be dried in limited spaces, said apparatus being set forth in the following specification and claims, and illustrated in the accompanying drawings, in which—

15 Figure 1 represents a transverse vertical section in the plane x , Fig. 2. Fig. 2 is a plan view. Fig. 3 is a detail view showing a roller mounted on a hollow axle, which is connected to a heating-pipe. Fig. 4 shows a 20 modification.

Similar letters indicate corresponding parts.

A is a base or support, which may be constructed of any material suitable for the purpose, and which may be in a horizontal position 25 or in a vertical position, or in any position suitable for the purpose. On this base a series of axles, B, B', B², B³, B⁴, B⁵, B⁶, B⁷, and B⁸, are mounted parallel to one another and on a spiral or approximately spiral line. The 30 term "spiral" is used in this case not strictly in the geometrical sense, but to indicate a line which recedes from its pole by irregular steps, although, if desired, said axles may be placed on a geometrical spiral without destroying the efficiency of the apparatus. On the base or 35 support is also mounted an interior exit-roller, C⁹, on an axle, B⁹, which axle B⁹ is inclined. A supplemental interior exit-roller, C¹⁰, on an inclined axle, B¹⁰, can also be provided.

40 A convenient way of attaching the axle B¹⁰ is to form said axle as on the extension of the axle B⁹. Other means of attachment may, however, be provided, the object being to place the supplemental exit-roller C¹⁰ at some distance 45 from the base or support A. Said inclined rollers C⁹ and C¹⁰ are loosely mounted on their axles.

On the axles B to B⁸ are loosely mounted 50 rollers C to C⁸, and, if desired, one or more of these rollers may be provided with pulleys, so that a rotary motion can be imparted to the

same. Between the rollers are a series of heating-coils, D. E represents the web which is to be dried. As indicated by the arrows in Fig. 2, this web is introduced into the drying 55 apparatus over the vertical roller C, and on reaching the interior inclined roller, C⁹, it is carried from the center or interior of the spiral up to the exterior inclined roller, C¹⁰, whence it passes out of the apparatus. In order to be 60 able to conduct the web from the interior of the spiral out of the drying apparatus, the two inclined rollers, C⁹ and C¹⁰, have to be provided.

If the web has sufficient strength, it can be 65 drawn through the drying apparatus, and the rollers C to C¹⁰ will be revolved by the action of the web itself; but in most cases it will be desirable to impart to some or to all of said rollers a revolving motion by belts or pulleys 70 or by other equivalent means.

By referring to Fig. 2 it will be seen that only one side of the web is brought in contact with the rollers C to C¹⁰ as the same passes through the drying apparatus, and my apparatus can therefore be used with advantage 75 for drying webs which have been colored, printed, or stained on one side without danger of injuring the designs or the colors produced on or applied to said web.

If desired, the supplemental exit-roller C¹⁰ 80 can be dispensed with and the fabric led off directly from the interior inclined exit-roller C⁹. As seen in Fig. 3, the rollers, or one or more of the rollers—as, for example, the roller 85 C—can be mounted on a hollow axle, B, communicating by a suitable connection with a steam-pipe, D. The rollers will thus be heated, and drying of the fabric is expedited. If desired, instead of leading the material into the 90 apparatus at the roller C and out at the roller C¹⁰ or roller C⁹, the material may be fed in at the roller C¹⁰. It should also be noticed that, in place of mounting the exit-roller on an inclined axle, the axle may be placed parallel to 95 the other axles, and the surface of the exit-roller be inclined, as seen in Fig. 4. The surface of the supplemental exit-roller may be similarly inclined, if desired.

What I claim as new, and desire to secure 100 by Letters Patent, is—

1. The combination of a series of rollers

mounted on parallel axles which are situated on a spiral line on a suitable base, with an inclined interior exit-roller and a supplemental inclined exterior exit-roller situated at a distance from the base or support, substantially as described.

2. The combination of a series of rollers mounted on parallel axles which are situated on a spiral line on a suitable base, with an inclined interior exit-roller, substantially as described.

3. The combination of a series of rollers mounted on parallel axles which are situated on a spiral line on a suitable base, with an inclined interior exit-roller and a heating-pipe, substantially as set forth.

4. The combination, with a heating-pipe, of a series of rollers mounted on parallel hollow axles communicating with said pipe and situated on a spiral line on a suitable base, and 20 an inclined interior exit-roller, substantially as set forth.

In testimony whereof I have hereunto set my hand and seal in the presence of two subscribing witnesses.

GUSTAV L. JAEGER. [L.S.]
